UNITED STATES PATENT OFFICE.

MICHAEL JANZUCK, OF KOKOMO, INDIANA.

CORE-MOLDING MACHINE.

1,381,310.

Specification of Letters Patent. Patented June 14, 1921.

Application filed October 4, 1920. Serial No. 414,535.

To all whom it may concern:

Be it known that I, MICHAEL JANZUCK, a citizen of Poland, residing at Kokomo, in the county of Howard and State of Indiana, have invented certain new and useful Improvements in Core-Molding Machines, of which the following is a specification.

This invention relates to core making machines and is designed primarily for making cores used in molding, one of the features of the invention being the provision of a hopper into which material for forming the cores is placed, said hopper having means therein for forcing the core forming material through a nozzle to shape the core.

A further feature of the invention is the provision of means for mixing sand, or the like, with the material of which the core is constructed, means being provided for causing the sand, or the like, to gradually feed into the hopper.

A further feature of the invention is the provision of means for mixing the sand with the other core forming ingredients and feeding the mixture toward the worm within the hopper.

A further feature of the invention is the provision of a core receiving table, said table having parts which travel intermittently for successively positioning a tray to receive the cores as they are discharged from the off-bearing device.

A further feature of the invention is the provision of means for removably attaching the nozzle to the hopper of the device so that cores of different diameters may be formed.

A further feature of the invention is the provision of means for operating the various parts of the molding device.

Other objects and advantages will be hereinafter more fully set forth and pointed out in the accompanying specification.

In the accompanying drawings which are made a part of this application,

Figure 1 is a top plan view of the molding device complete,

Fig. 2 is a side elevation thereof,

Fig. 3 is a sectional view as seen on line 3-3 Fig. 1,

Fig. 4 is an enlarged detail sectional view as seen on line 4-4 Fig. 1,

Fig. 5 is a sectional view as seen on line 5-5 Fig. 4,

Fig. 6 is an enlarged fragmentary elevation of parts of the core receiving table and the off-bearing mechanism, and

Fig. 7 is a perspective view of the off-bearing mechanism.

Referring to the drawings in which similar reference numerals designate corresponding parts throughout the several views, 1 indicates a hopper which may be constructed in any preferred manner, having at one end a tubular extension 2 for the reception of a core forming tube or mold 3, said tube being interchangeable, so that cores of varying diameters may be formed. Positioned above the hopper 1 is a funnel-shaped member 4 into which sand or similar substance is placed to be mixed with the contents of the hopper, the contents of the funnel-shaped member gradually feeding into the hopper.

Extending transversely through the lower portion of the hopper 1 is a shaft 5 on which is mounted a worm 6, said worm being so arranged that it forces the contents of the hopper into the tubular extension 2 and through the tubular mold 3, said shaft being rotatably mounted in a suitable bracket 7. The worm 6 is driven from a pulley 8 on a line shaft 9 through the medium of a belt 10, said belt passing around a driving pulley 11 on a shaft 12, said shaft 12 having a gear 13 thereon which meshes with a gear 14 on the shaft 5. The shaft 12 is also provided with an idler pulley 15 so that when the belt 10 is shifted onto said idler pulley the worm 6 will remain stationary.

In order to thoroughly commingle the core forming product with the contents of the funnel-shaped member 4, combined mixing and tamper heads 16 are positioned within the hopper 1 and connected with arms 17, which arms are substantially U-shaped and project through elongated slots 18 in one end wall of the hopper 1, the outer ends of said arms being eccentrically attached to disks 19 rotatably supported on the end wall of the hopper. The disks 19 are provided with pulleys 20 around which extends a belt 21, said belt also extending around a pulley 22 on shaft 5, and by means of which the disks 19 are driven and it will be readily seen that as the disks rotate the arms 17, and the heads 16 carried thereby will be raised and lowered thereby commingling the contents of the hopper and forcing the same downwardly in the path of the worm. In order to cause the contents of the funnel-shaped member to

gradually feed into the hopper 1, a bar 23 is pivotally attached to a bracket 24 on one face of the hopper, one end of the bar being bent inwardly so that it will be in position 5 to strike one face of the funnel-shaped member while the opposite end of the bar is extended inwardly so as to contact with a toothed wheel 25, said wheel being mounted upon a shaft 26 suspended from the bracket 10 7. The teeth on the wheel 25 swing the upper end of the bar 23 outwardly, and when released from the teeth a spring 27 will draw the upper end of the bar inwardly and deliver a blow on the funnel-shaped member 15 4, thereby jarring the contents of said funnel-shaped member and causing it to feed through the restricted portion thereof. The shaft 26 is rotated from the shaft 5 by placing a pulley 28 on the shaft 5, and a pulley 29 on the shaft 26, a belt 30 passing around 20 said pulleys.

As the cores, when they leave the molding tubes 3, are more or less plastic it is necessary to deposit the cores on a tray with considerable care, and to accomplish this result 25 an off-bearing member 31 is provided which comprises a plurality of trough-like members 32, which are attached together and mounted upon a shaft 33, so that they will 30 successively rotate and be positioned to receive the core as it is discharged from the molding tube 3, the curvature of the members 32 being such that as the off-bearing member 31 rotates the cores will be rolled 35 onto a tray 34. The off-bearing member 31 is positioned horizontally above a table 35, said table including chains 36 which pass around sprocket wheels 37 at the ends of the table and below sprocket wheels 38 40 adjacent the lower portion of the table, the sprockets 37 and 38 being mounted upon shafts 39 and 40 respectively. Extending transversely of the travel of the chains 36 are cross bars 41, and in order to form a 45 cushion for the tray 34, so that no appreciable jar will be given the cores as they are deposited on the tray, the cross bars are mounted upon springs 42. The table 35 is preferably inclined slightly toward its outer 50 end, thereby positioning the tray at a slight inclination and causing the successive cores as they are deposited upon the tray to move into close proximity to the preceding core. The cores are severed into lengths by providing each trough-like member 32 with a curved knife 43, said knives being arranged at the ends of the trough-like members adjacent the outer end of the tube 3, the knives being so arranged that they will sever the 55 core as the off-bearing member starts to rotate. The shaft carrying the off-bearing member 31 is positioned at one side of the axis of the tube 3, and the member is driven from the shaft 40 through the medium of 60 sprockets 44 and 45 on the outer end of the 65

shaft of the off-bearing member 31 and the shaft 40 respectively, consequently the driving means for the off-bearing member 31 will be entirely out of the road of the cores.

The chain 36 is driven from a pulley 46 70 on the line shaft 9 through the medium of a belt 47, said belt passing around a pulley 48 mounted on a shaft 49, which pulley in this instance is an idler, said shaft also having a driving pulley 50 thereon, so that when the belt is shifted onto said pulley the chain 36 and parts connected therewith will be driven. In order to drive the chain 36 in the right direction a gear 51 is mounted on the shaft 49 with which meshes a gear 52 on 80 a shaft 53, said shaft 53 having a belt pulley 54 thereon, around which passes a belt 55, said belt also passing around a pulley 56 on the inner end of the shaft 40.

In operating this device it is the intention to have the molding arrangement remain idle while the off-bearing operation is being performed, and to have the off-bearing parts remain idle while the molding operation is being performed, and any suitable means may be provided for accomplishing this result, but as shown in Fig. 1, any suitable form of belt shifts 57 and 58 may be provided for moving the belts 10 and 47 respectively, into operative or inoperative 90 positions, and it will be understood, of course, that the power may be disconnected from both the molding machine and the off-bearing mechanism simultaneously. The line shaft 9 is operated from any suitable form 100 of motor 59, which is connected with a pulley 60 on line shaft 9 by belt 61. In operation when the core is to be molded the belt 10 is positioned as shown in Fig. 1, and when power is applied to the line shaft 9 the 105 worm 6, and parts associated therewith will be driven, forcing a core through the molding tube 3 and depositing the same on one of the trough-like members 32. When the proper length of core has been molded the 110 belt 10 is shifted onto the pulley 15 and stopping the operation of the worm 6, while the belt 47 is simultaneously moved onto the pulley 50 which will set up operation of the off-bearing mechanism, and parts associated 115 therewith. As the off-bearing member 31 rotates the knife 43 adjacent the end of the molding tube will sever the core, and as the trough-like member swings downwardly the core will be gradually rolled from off the 120 trough-like member and deposited upon the tray 34. As soon as the off-bearing member has rotated a sufficient distance to bring a new trough-like member in position to receive the next core from the molding tube 3, the belt 47 is shifted back to the pulley 48 thereby stopping the operation of the off-bearing mechanism; simultaneously with the rotating of the off-bearing member to 125 deposit the core on the tray the chain 36 130

will be given a slight endwise movement thereby advancing the tray a sufficient distance to deposit the new core immediately in the rear of the preceding core, the slight inclination of the tray causing the newly deposited core to snugly nest near the preceding core. As soon as the prescribed number of cores has been deposited on the tray, said tray is removed and a new tray inserted on the cross bars 41 and ready to receive additional cores.

By forming the cores in this manner the operation is greatly facilitated and a more perfect core is produced as the cores are not manually handled until such time as they have become sufficiently set to retain their shape. It will likewise be seen that cores of various diameters may be made by changing the size of the molding tubes 3, and it will be likewise seen that by employing the combined mixing and tamping heads 16, the product of which the cores are formed will be of the proper consistency as the ingredients composing the same are uniformly commingled.

Having thus fully described my said invention, what I claim as new and desire to secure by Letters Patent, is:

1. In a core molding device, a hopper adapted to contain products for forming cores, a mold connected with said hopper, means for forcing the contents of the hopper through the mold for forming a core, a rotatable off-bearing member for receiving the core from the mold, means for severing the core, a receptacle for receiving the cores, and means for rotating the off-bearing member for depositing the core on the receiving member.
2. In a core molding machine a hopper adapted to contain ingredients to be formed into a core, a member above said hopper for containing one of the ingredients of the core forming mixture, means for successively delivering blows on said member for causing the contents thereof to feed into the hopper,

means for thoroughly commingling the contents of said member with the contents of said hopper and for forcing said contents downwardly in the hopper, a molding tube 50 attached to the hopper, and means for forcing the contents of the hopper through said tube for forming a core.

3. The combination with a core molding device, of a rotatable off-bearing member, a tray for receiving the cores from the off-bearing member, means for yieldingly supporting the tray, and means for intermittently moving the tray for receiving additional cores from the off-bearing member. 60

4. The combination with a core molding machine, of an off-bearing member for receiving the cores as they are discharged from the molding machine, comprising a plurality of trough-like members, means for successively rotating the trough-like members to position them to receive the cores from the molding machine, and means operable with the trough-like members for severing the cores. 70

5. The combination with a core molding machine, of an off-bearing member arranged to receive a core from the molding machine, a tray for receiving the cores from the off-bearing member, and means for operating 75 the off-bearing member for causing the cores to descend by gravity onto the receiving tray.

6. The combination with a core molding machine, of a revolving off-bearing member 80 arranged to cause the core to leave the off-bearing member with a rolling movement whereby the shape of the core will be maintained.

In witness whereof, I have hereunto set 85 my hand and seal at Indianapolis, Indiana, this 25th day of September, A. D. nineteen hundred and twenty.
